UNITED STATES PATENT OFFICE.

GEORGE W. KELLOGG, OF ROCHESTER, NEW YORK, ASSIGNOR TO WRAY PUMP & REGISTER COMPANY, OF ROCHESTER, NEW YORK, A CORPORATION OF NEW YORK.

AIR-PUMP.

No. 885,485.

Specification of Letters Patent. Patented April 21, 1908.

Application filed November 1, 1906. Serial No. 341,637.

To all whom it may concern:

Be it known that I, GEORGE W. KELLOGG, a resident of Rochester, in the county of Monroe and State of New York, have invented certain new and useful Improvements in Air-Pumps; and I do hereby declare the following to be a full, clear, and exact description of the invention, such as will enable others skilled in the art to which it pertains to make and use the same.

The invention relates to pumps, and has for its object to increase the efficiency, and diminish the labor of operation of a pump of simple and compact construction.

The invention consists in the construction hereinafter described and pointed out.

In the accompanying drawing which illustrates the invention,—Figure 1 is a longitudinal section of the pump, the cylinders being shown in an intermediate situation; Fig. 2 is a view indicating a modification; Fig. 3 is a longitudinal section illustrating a modification.

Numerals 1 denotes a base or support of any approved character, and 2 a check valve in an exit or delivery pipe 3, communicating through the valve port with a cylinder 4 supported on the base.

Numeral 5 indicates a larger cylinder mounted to reciprocate in a telescoping manner on the exterior of cylinder 4.

A tubular piston rod is indicated at 6, and is fixed to cylinder 5, and 7 denotes a piston having a flexible cup-valve-packing 8.

A spring-supported check valve is denoted by 9.

The piston rod is movable through a stuffing box 10 which is fixed upon the end of the inner cylinder. A cup or valve packing is denoted by 11, and a handle for actuating the pump by 12.

13 indicates one or more inlets near the lower end of cylinder 5, and 14 one or more inlets at or near the upper end of tube 6, whereby said cylinder 5 and tube 6 communicate.

15 denotes an exit or delivery port at or near the lower end of cylinder 4, and 16 are ports by which air passes from tube 6 into the lower cylinder around its piston.

In operation air is admitted through a port or ports 13, which will be situated above the stuffing box and its flexible packing 11 when the outer cylinder is at or near its highest situation. At such time outside air enters

the upper cylinder. When said port 13 is below the level of the stuffing box air freely enters or escapes from the annular space 18 between the cylinders. If the upper cylinder, having been raised and filled with air, entering through port or ports 13, as stated, be forced down its contained air is driven through ports 14 into and through tube 6 and out through ports 16 into the space between the piston and the stuffing box. The descent of the outer cylinder, and of the piston fixed thereto, forces the air which is below said piston past the check valve 2 and through the delivery tube to a wheel tire or other receptacle. When the outer cylinder and the piston fixed to it are again raised the air between the piston and stuffing box escapes through the passage or port around the piston into the lower cylinder to be forced out as before past the check valve by the next down stroke of the outer cylinder and the piston.

Obviously instead of relying upon the passage of air down around the flexible packing, it might be forced through a port closed by a check valve, as indicated in Fig. 2, in which the piston is denoted by 7 and the check valve by 7^x. These devices are well known equivalents for admitting air below or in front of a retreating piston.

The construction and operation of the device are such that air compression is effected by a movement in one direction, which may be downward so that the operator can make his weight contribute to the power required. This method is more convenient and agreeable to the operator, and is secured by the simple and compact construction and arrangement of parts described.

As shown in Fig. 3, the exterior cylinder 5 receives air through one or more ports 13 whenever said cylinder and its connected piston 7 are actuated to compress air in cylinder 4. In the reverse movement the air from cylinder 5 passes through ports 21 and past the flexible packing 20 provided to prevent return of air to cylinder 5. In this case a solid piston rod 6^x can be used, as indicated. In this form air compression is effected substantially as above stated.

The air inlet or inlets 13 are situated substantially as illustrated whereby in the up stroke, that is, the stroke that carries inlet 13 above the packing 11 and admits air above the packing, said stroke is cushioned

110

- by air then confined in the lower part of the outer cylinder 5, and whereby in the beginning of the reverse or compressing stroke said inlet is passed below the packing with 5 the effect to drive practically all air then forced from the upper end of the outer cylinder into the lower cylinder instead of returning said air to the exterior of the pump. It is obvious that the pump may be so held that 10 the stroke for compression may be down or up or in any other direction desired but preferably it will be down as set forth.
- Having described the invention what I claim is,—
- 15 1. In a pump, the combination of the fixed and movable telescoping cylinders, the movable piston having a tubular rod and fixed thereby to the movable cylinder, said piston being operated in the fixed cylinder, and 20 suitable ports whereby both cylinders are filled when they are extended and whereby air is compressed and delivered when one cylinder is telescoped within the other.
2. In a pump, the combination of a movable cylinder, a piston rod fixed to said cylinder, a fixed or stationary cylinder, a stuffing box between the cylinders and fixed to said stationary cylinder, a piston fixed to said rod and operative in the stationary cylinder, and suitable ports whereby air is admitted to both cylinders when the piston is moved in one direction and compressed when it is oppositely moved.
3. In a pump, the combination of the outer cylinder, the inner cylinder, the stuffing box fixed to the inner cylinder and bearing on the interior of the outer cylinder, the air inlet in the outer cylinder adapted to be moved past said box to admit air to the outer cylinder during the down or air-compressing stroke, the piston actuated through the medium of the outer cylinder and operative within the inner cylinder, and means whereby to admit air directly from the outer to the inner cylinder.
4. In a pump, the combination of the outer and inner cylinders, the stuffing box fixed to the inner cylinder, the piston actuated through the medium of one cylinder and operative in the other, an air inlet in the periphery of the outer cylinder near its lower end and movable thereby past said box, and passages all substantially as described where-
- by air admitted during one movement of the piston may be compressed during a return movement, all exterior air being admitted through said inlet in the outer cylinder.
5. In a pump, the combination of two telescoping cylinders, a stationary valve packing and cap fixed to the end of the inner cylinder and bearing on the outer cylinder, said cap being perforated, said latter cylinder having an air inlet in its periphery near its end whereby air is successively admitted to the outer cylinder below and above said packing and without passing between the packing and outer cylinder.
6. In a pump, the combination of two telescoping cylinders, a relatively stationary valve packing between said cylinders, and a piston actuated by the exterior cylinder, said exterior cylinder having its sole means of air admission in its periphery adjacent the said packing.
7. In a pump, the combination of an outer movable cylinder having a closed end, a rod fixed to said end and provided at its opposite end with a piston, an inner stationary cylinder coöperating with said outer cylinder and piston, a valve packing between the cylinders, and suitable ports to admit air to both cylinders including a port adjacent said packing admitting exterior air directly to the outer cylinder on either side of said packing according to the situation of the cylinders, 85 the outer cylinder containing an air chamber closed except for the packing when said packing is below the port.
8. In a pump, the combination of the telescoping cylinders, the piston fixed to the outer cylinder, a packing between the cylinders, and an air port admitting air to either side of said packing according to the movement of the outer cylinder, whereby the upstroke of the outer cylinder is cushioned and whereby in the down stroke direct communication with the outer air of the outer cylinder above said packing is cut off.
- In testimony whereof, I have signed this specification in the presence of two subscribing witnesses.

GEORGE W. KELLOGG.
